INTERCHANGEABLE PUNCH AND DIE
AND RETAINER FOR SAME

Dominic V. Stellin, Detroit, Mich.

Application March 6, 1944, Serial No. 525,233

6 Claims. (Cl. 164—118)

The present invention pertains to novel interchangeable punches and dies and particularly to devices for accurately locating and retaining the punches and dies.

The principal object of the invention is to provide such retaining and locating means for punches and dies that are intricate and not necessarily round. Hitherto it has been the practice to interchange round punches and dies requiring no particular accuracy in being located. Obviously the means employed in that connection would not be suitable for non-round or intricate parts.

Another object of the invention is to provide interchangeability of the character described by simple means requiring comparatively little time in making a change. This object of the invention is of great importance in urgent production, as in war work, and in mass production where a given rate of output must be maintained in order to yield a profit. The loss of time incident to changing of punches and dies for any reason, such as breakage or need of sharpening, is substantial. A reduction of this loss by use of the present invention results in an important economy in the over-all operation.

Among the intricate punches and dies for which the invention is adapted are slitting punches, which can not be properly located in a simple manner by existing devices. These punches are made of hardened steel, and when used on cutting hard material such as high carbon spring steel, the clearances between punches and dies is approximately 5% of the thickness of the metal, and therefore accurate locating of punches and dies is essential. In many cases the effective height of the punches must be accurately maintained, or the dimensions of the resulting slit will be affected. The locating means for a pair of slitting punches is described hereinafter.

In general the locator is so designed as not to require disassembling the main retainer or body that receives the punch or die. In the simplest form of the invention, the punch or die is formed with one or more keyways receiving a locating member fastened to the retainers. The fit of the locator in the keyways is accurate and permits no rotation or slipping of the punch or die. Moreover, the locator is quickly applied and maintains the punch or die accurately located.

Other forms of the invention provide the locator or key in various positions in the retainer body. In one case the locator is positioned between the upper and lower surfaces of the body; in another case between the inner surface of the

body and the press plate. The invention also embodies various forms of keying means as well as several forms of locking devices therefor, such as holding clips and spring retainers.

5 The invention is fully disclosed by way of example in the following description and in the accompanying drawings in which

Figure 1 is a vertical section of a punch and die, according to one embodiment of the invention;

Figure 28 is a vertical section of a die with a dual locating means;

Figure 29 is a plan view of another embodiment, and

Figure 30 is a section on the line 30—30 of Figure 29.

Reference to these views will now be made by use of like characters which are employed to designate corresponding parts throughout.

In Figure 1 are shown a punch and die embodied in one machine as well known in the art. The die plate 1 is ordinarily immovable in the operation of a machine and has a die retainer 2 mounted thereon. The retainer is secured to the die plate by suitably disposed Allen screws 3 and is located by intervening diagonally disposed dowel pins 4 as also well known in the art. The retainer 2 has a recess 5 in which the die 6 is inserted. Assuming that the die is to be used in forming a circular opening, it has such an opening 7 in its upper end communicating with a wider cavity 8 in the body of the die to admit the punch and to permit some accumulation of slugs.

The upper surface of the retainer 2 is formed with a keyway 9 which is diametrical of the recess 5 and disposed at both sides thereof. The surface of the die 6 is formed with a pair of opposed and parallel transverse grooves 10 which have their bottoms in the same plane with the bottoms of the keyway 9 when the die is fully inserted, although the grooves are wider than the depth of the keyway as may be seen in Figure 1. The grooves 10 in the die may be aligned with the keyway 9 in the retainer.

The purpose of the keyway and the grooves is to receive a fork-shaped locator having a stem 12 and a pair of fingers 13. The fork is inserted in the keyway 9 from either end of the recess 5, and each finger 13 is also received in a groove 10 of the die.

In order to retain the die in its retainer, it is now only necessary to fasten the locator to the retainer. For this purpose, the stem 12 is formed with a longitudinal slot 14 through which a locking screw 15 is passed and threaded into the retainer. A finger piece 16 is provided on the free end of the stem 12 for conveniently adjusting the forked locator before tightening the screw 15 in its hole 22.

The modified locator is preferably formed of suitable steel and carries a locking pin 18 at the free end of the stem. The pin is sprung into a recess 20 in the face of the retainer 2 to prevent the locator from slipping after it has been locked by the screw. A hardened backing plate 21 may be mounted under the die, especially for heavy work.

The punch assembly is similar and includes a punch plate 23 beneath which a retainer 24 is secured by Allen screws 25 and dowels 26. The retainer has a recess 27 for receiving a punch 28 and is formed in its face with a wide keyway 29 similar to the keyway 9. The punch is formed with opposed transverse and parallel grooves 30 adapted to register with the keyway 29 formed at both sides of the recess 27. Behind the punch is provided a hardened backing plate 31. Obviously such backing plates may be provided in the succeeding views, if desired.

A forked locator 32, similar to that previously described, is received in the keyway 29 and has its arms 33 projected into the grooves 30 formed in the punch. A screw 34 passed through the slotted stem 35 of the fork and into the retainer

24 secures the locator which in turn holds the punch from falling out of its retainer.

Due to the parallel relation of the grooves 10 and of the grooves 30, the punch and die are held against rotating in their respective retainers. For this reason the forked member is designated a locator. Although rotation of the punch is permissible for circular members, even a slight rotation of non-circular punches and dies would exceed the limit of tolerance and damage or break one or the other. The application of a locator for preventing rotation will be pointed out more fully hereinafter.

Figure 4 shows a modified retainer with a conventional punch and die assembly, the usual parts of which need therefore not be described in detail. The die 40 is formed in its wall with notch 41 at the face of the retainer 42. On the retainer is mounted a sliding lock 43 having a square end 44 adapted to enter the notch 41 and abut the bottom thereof. The member 43 has a lengthwise slot 45 adapted to receive a screw 46 which threads into the retainer 42.

The sliding lock 43 is preferably made of suitable steel and carries at its free end a pin 47 adapted to enter a corresponding recess 48 in the face of the retainer 42. This device prevents the sliding lock from sliding on the retainer after it has been set.

Similarly, in the punch assembly the punch 40 has a lateral notch 49 receiving the sliding lock 50 which is supported and retained in the manner already described.

As shown in Figure 1, the sliding lock 51 may have a rounded entering end 52, and the punch or die 53 has a correspondingly shaped receiving notch 54. In the further modification shown in Figure 7 the sliding lock 55 is held by a stud 56 on which is mounted a tightening nut 57.

More accurate and secure locating of an intricate punch and die is obtained by the construction shown in Figures 8 and 9. The retainer 60 of the die has a vertical key slot 61 communicating with the die recess 62. The die 63 has a longitudinal or vertical slot 64 adapted to register with the slot 61. A key 65 of such size as to fill both slots is inserted in the slot 64 before the die is inserted in its retainer. On insertion of the die, the key will also enter the slot 61 and thereby locate the die against rotating.

The locking key is a flat member 66, similar to those previously described, mounted on the retainer 60 and adapted to enter a notch 67 in the die. The key or locator 66 is attached to the retainer by a screw 68 passed through a slot 69 in the locator. The latter has a finger piece 70 and may also have a stop 71 adapted to enter a recess 71' in the top of the retainer.

The punch 72 of the assembly is mounted in its retainer 73 in like manner. It has a longitudinal slot 74 matching with a similar slot 75 in the retainer, both slots receiving a key 76 fitted in the punch before inserting the punch in the retainer. The exposed portion of the punch has a notch 77 receiving one end of a locking key 78 mounted on the retainer by a screw 79 in substantially the manner previously described.

A modified arrangement of locking key or locator is shown in Figures 10 to 12. With reference first to the die assembly, this comprises the usual plate 80 to which is attached a retainer 81 by means of alternate bolts 82 and dowels 83. The retainer has a recess 84 which receives the die 85. Registering slots 86 and 87 are cut re-

spectively in the retainer and die between the upper and lower planes of the retainer and extending entirely through the retainer to be exposed at opposite lateral surfaces thereof. A key 88 is fitted in the registered slots 86, 87. In this particular embodiment, the key is made of key stock and is of substantially square cross-section.

Adjacent to each end of the slot 86, the retainer has a tapped hole 89 for the attachment of a spring clip or lock to the retainer by means of a screw 91 passed through a hole 92 in the clip and into the hole 89. The member 90 is made of spring steel and carries at its free end a pin 93 which enters a recess 94 in the adjacent end of the key 88. Both ends of the key are so recessed, inasmuch as a spring lock is mounted at each hole 89 in the opposed surfaces of the retainer 81.

The key 88 may be replaced by a clevis pin 95 in Figure 12 having a head 96 at one end and receiving a cotter pin 97 at the other end. Another device for the same purpose is a bolt 98 having a head 99 at one end and carrying a nut 100 at the other end, as in Figure 13.

A similar arrangement is employed for the punch assembly which comprises the usual plate 101 and retainer 102 having a recess 103 and attached to the plate by bolts 104 and dowels 105. The punch 106 and the wall of the recess 103 are formed respectively with registering slots 107 and 108 in which is inserted a key 109 as previously described. Likewise, each of the opposed surfaces of the retainer, at the ends of the slot 108, is formed with a tapped hole 110 for attaching a spring clip adapted for reception in a depression 112 in the adjacent end of the key, as previously set forth. As an alternative construction, the slots in the retainer, die and punch may have a blind end and thus require a holding clip only at the single exposed end.

In the construction shown in Figure 14, the retainer 115 and die 116 are formed with semi-cylindrical registering slots 118 and 119 which receive a cylindrical key 120, which may be made of drill rod. Each end of the key is retained by locking clips 120' mounted on opposed surfaces of the retainer 115 as previously described. Likewise, the punch retainer 121 and the punch 122 are formed with registering semi-cylindrical slots 123, 124 in which is inserted a cylindrical key 125 held at both ends as previously described.

Figures 15, 17 and 19 show a construction in which the punch or the die is located by a key at the base thereof or between the plate and the retainer. Figure 15 shows a shear punch consisting of two punch members rather than a punch and a die. The assembly of only the punch members need therefore be described, with the same reference characters applicable to like parts of both assemblies.

The plate 130 carries a retainer 131 by means of bolts 132 and dowels 133 in the usual manner. The surface of the retainer immediately adjacent to the plate is formed with a keyway 134 extending into communication with the punch receiving recess 135. Diametrically opposite this point of communication, the retainer is formed with a relatively larger recess 136 also communicating with the recess 135.

The inner end of the punch 137 is formed with a keyway 138 registering with the keyway 134 and communicating with the recess 136. A key 139 is inserted in the aligned keyways before attaching the retainer 131 and cannot be withdrawn

without removing the retainer. The key 139 has a hooked end 140 received in the recess 136 and re-entrantly into a notch 141 formed in the adjacent wall of the punch 137.

The key holds the punch against rotation, and it is now only necessary to maintain the hooked end 140 in the notch 141. For this purpose the retainer is drilled with a diagonal hole 142 leading to a bevelled edge and tensioned by a flat set screw 145 threaded in the outer end of the hole 142. The punch is released from the hook 140 by inserting a pin or wire in keyway 134 against the end of the key to push it against the tension of the spring 144, with or without retracting the screw 145.

Figure 17 shows a similar relation of punch 150 and key 151 having a hooked end 152 extending into a notch 153 in the punch. The hole 154 in the retainer 155 communicating with the recess 156 for the hook 152 is radial of the punch. The hole receives a coil spring 157 bearing against the hook 152 in the axial direction of the key 151 and is tensioned by a flat screw 158 threaded into the outer enlarged end of the hole 154.

The shear punch shown in Figure 15 is designed to punch a hole 160 in ribbon stock 161 (Figure 16) and has a sharp edge 162 for forming opposed slits 163 extending radially outward from the hole 160. The shearing action of the punch forms an arcuate slit 164 at the outer end of each radial slit 163. A series of punchings is formed in the stock by multiple punches or successively by one pair of punches. The stock is severed between the punches, and each section is suitable for the formation of a lock washer of the character shown in my United States Patents Nos. 2,191,101 and 2,274,010.

A slight modification of the last described mounting is shown in Figure 18 wherein the hooked end 170 of the key is engaged by a stud 171 threaded through the retainer 172 and locked by a jam nut 173. In the further modification shown in Figure 19, a spring 175 surrounds the screw 176 within the recess 177 for the hooked end 178 of the key and exerts pressure against said end. In such case the stud 176 need not rigidly engage the hooked end 178.

In the construction shown in Figure 20, the retainer 180 likewise has a key slot 181 in its surface immediately adjacent to the plate 182. This keyway is, however, similar on both sides of the punch-receiving recess 183. The inner end of the punch 184 mounted in the recess has a keyway 185 receiving key 186 mounted in the keyway 181. The key is mounted before securing the retainer 180 to the plate 182 and is secured on tightening the bolts 187.

A diagonal hole 188 is drilled in the retainer 180, and the punch 184 is formed with a notch 189 shaped as a continuation of the hole. In the hole is mounted a cylindrical locator or holder 190 having a bevelled end 191 that partially enters the notch 189. The locator is advanced by a coil spring 192 which is tensioned by a flat screw 193 threaded into an enlargement 194 of the hole 188.

In the corresponding construction for the die, the retainer 195 is formed with a similar keyway 196 in the surface adjacent to the plate 197. The die 198 is hollow and is formed at its inner edge with opposed keyways 199 adapted to receive keys 200 projected therein from the keyways 196.

75 The die is hollow and the keys are not permitted

to enter the cavity, in order to leave a clear opening for the slugs.

The retainer is formed with a diagonal hole 201 directed towards the die which is formed with a notch 202 as an extension of the drill hole. A cylindrical bevelled locator 203 is inserted into the hole and into the notch 202 and is backed by a coil spring 204 which in turn is tensioned by a flat screw 205. In order to remove either the punch or the die, the screw is retracted, whereupon the locator may readily be withdrawn.

In the modification shown in Figure 22, the retainer 210 has a square hole 211 to receive the bevelled locator 212, the bevelled end of which enters a notch 213 in the punch 214. The retainer 215 and the punch are formed with aligned keyways 216 and 217 respectively for receiving the locking key 218.

Another construction of locator is shown in Figure 23. In this case the retainer 220 has a radial hole 221 drilled from the punch receiving cavity 222. The punch 223 has a conical recess 224 registering with the hole 221. The punch is held against rotation by a key 225 adjacent to the plate 226 in the manner previously described. The retainer has a slot 227 extending from its wall to the hole 221. In the hole is mounted a locator in the form of a cylindrical member 228 having a pointed end 229 entering the notch 224. The locator is inserted from the cavity 222 against a tensioned spring 230. The locator has a small hole 220' at the slot 227, which may be reached by a wire or other suitable object passed through the slot to withdraw the locator for permitting insertion or withdrawal of the punch.

The die 231 is held in like manner in its retainer 232 and against its plate 233 by a locator assembly similar to that just described and designated generally by the numeral 234. The die has a conical notch 235 to receive the locator pin as previously described. The keys 236 entering the die do not obstruct the cavity therein.

Another modification of the intermediate key type is shown in Figure 24. The retainer 240 is fastened to the plate 241 by bolts 242 and is located by dowels 243 in the usual manner. The retainer has a recess 244 receiving the punch 245 in the usual manner. The wall of the latter has a longitudinal key 246 between its ends.

A cavity 247 is drilled from the recess 244 horizontally in the retainer 240 and is counterbored at 248 in a smaller dimension, the counterbore terminating inward of the lateral wall of the retainer. The locator is in the form of a plate 249 mounted in the hole 247 and having a reduced stem 250 extending in the counterbore 248 and through the lateral wall of the retainer. The inner face of the plate 249 is formed with a key 251 entering the key slot 246. A coil spring 252 surrounds the stem 250 to move the locator toward the punch, and the exposed outer end of the stem carries a cotter pin 253 which prevents the locator from being withdrawn from the retainer 240.

As an alternative construction, Figure 26, the stem 250a has its exposed outer end threaded at 254 to receive a retaining nut 255. In another alternative form, Figure 27, the exposed outer end of the stem 250b has a wire loop 256 passed therethrough to replace the cotter pin and also to serve as a pull ring.

Figure 28 shows another modification of the dual key locator, illustrated here in connection with the die. The retainer 260 for the die is 75

formed with two recesses 261 immediately adjacent to the plate 262 and in communication with the cavity 263 at diametrically opposite points thereof. The hollow die 264 set in the cavity has 5 diametrically opposed keyways 265 in the end that abuts the plate 262 and adapted to communicate with the recesses 261. The outer wall of the die also has a pair of notches 266 spaced slightly from the keyways.

10 Each recess 261 contains a locator 267 having a key extension 268 adapted to enter the corresponding keyway 265 and a finger 269 adapted to enter the corresponding notch 266. Between the extension and the finger, the locator has a bevel 270. A diagonal hole 271 is drilled in the retainer 260 for and in communication with each of the cavities 261 at the bevel of the inserted locator. Each hole contains a coil spring 272 engaging the corresponding bevel and tensioned by a screw 273 threaded into the outer end of the hole.

15 Figures 29 and 30 show more specifically a construction for a square or non-round punch or die. A retainer 280 is shown receiving a square die 281. The latter is formed with a slot 282 along one side and disposed outside the retainer. On the retainer is suitably mounted a locator 283 by means of a headed screw 284 passed through a slot 285 in the locator and fastened in the retainer. A straight edge 286 at one end of the locator enters the groove 282 and seats linearly against the bottom thereof, thereby accurately holding the die against shifting. The locator has a pin 287 received in a recess 288 in the retainer, as previously set forth, and is further formed with an actuating finger piece 298.

20 Various forms of locators, locating keys, etc., may be interchanged from one embodiment to another to suit requirements, wherever permitted by the construction involved. For example, the locator for the punch shown in Figure 28, and vice versa.

25 Although specific embodiments of the invention have been illustrated and described, it will be understood that various alterations in the details of construction may be made without departing from the scope of the invention as indicated by the appended claims.

30 What I claim is:

1. In a punch or die assembly, a plate, a retainer fastened thereto, said retainer having a keyway at said plate, a severing member received in said retainer and having a keyway registering with the first keyway, a key passed through both keyways and having a re-entrant portion extending into said severing member, and means for holding said portion in said member.

40 2. In a punch or die assembly, a plate, a retainer fastened thereto, said retainer having a keyway at said plate, a severing member received in said retainer and having a keyway registering with the first keyway, a key passed through both keyways and having a hook at one end, said member having a recess in its lateral wall receiving said hook, and means for holding said portion in said member.

45 3. In a punch or die assembly, a plate, a retainer fastened thereto, said retainer having a keyway at said plate, a severing member received in said retainer and having a keyway registering with the first keyway, a key passed through both keyways and having a hook at one end, said member having a recess in its lateral wall receiving said hook, and a spring received in said retainer and bearing against said hook to hold the hook engaged in said recess.

4. In a punch or die assembly, a plate, a retainer fastened thereto, said retainer having a keyway at said plate, a severing member received in said retainer and having a keyway registering with the first keyway, a key passed through both keyways and having a hook at one end, said member having a recess in its lateral wall receiving said hook, a spring received in said retainer and bearing against said hook to hold the hook engaged in said recess, and a screw in said retainer and bearing against said spring for tensioning the same.

5. In a die assembly, a plate, a retainer fastened thereto, a hollow die received in said retainer, the inner end of said die having opposed keyways, said retainer having a pair of opposed

keyways at said plate and registering with the first keyways, and an individual key in each pair of registering keyways and disposed outwardly of the cavity of the hollow die.

6. In a die assembly, a plate, a retainer fastened thereto, a hollow die received in said retainer, the inner end of said die having opposed keyways, said retainer having a pair of opposed keyways at said plate and registering with the first keyways, and an individual key in each pair of registering keyways and disposed outwardly of the cavity of the hollow die, each key having a hook, said die having a pair of recesses in its wall adapted to receive said hook and means for holding said hooks in said recesses.

DOMNICK V. STELLIN.
